A. R. THOMPSON.
SAFETY CAN FEED CHUTE.
APPLICATION FILED APR. 3, 1920.

1,394,799.

Patented Oct. 25, 1921.

UNITED STATES PATENT OFFICE.

ALBERT R. THOMPSON, OF SAN JOSE, CALIFORNIA, ASSIGNOR TO ANDERSON-BARNGROVER MFG. CO., OF SAN JOSE, CALIFORNIA, A CORPORATION OF CALIFORNIA.

SAFETY CAN-FEED CHUTE.

1,394,799.

Specification of Letters Patent. Patented Oct. 25, 1921.

Application filed April 3, 1920. Serial No. 370,936.

To all whom it may concern:

Be it known that I, ALBERT R. THOMPSON, a citizen of the United States, residing at San Jose, in the county of Santa Clara and State of California, have invented certain new and useful Improvements in Safety Can-Feed Chutes, of which the following is a specification.

My invention relates to can-feeding devices and particularly to that type or class of feeders in which the supports for the can are spaced by a distance greater than the diameter and but little less than the length of the can, so that unless the can enters upon 10 said supports square and true it will fail to bridge the space and will drop through and out of the can stream, without interfering with the continuity of said stream. An example of this type of can-feeding devices is 15 disclosed by my former Patent No. 1238217, dated Aug. 28, 1917, in which rotating turret disks are spaced and operate to carry the cans forward only when said cans register squarely upon them, but drop them down 20 between, when out of true.

My present invention, instead of employing the rotating turret disks, comprises a gravity chute, with properly spaced side supports, and means for nicely adjusting the 25 space to insure its delicacy of function or to adapt it for different lengths of cans.

The importance of a simple, effective and easily regulatable safety can feed chute may be seen from the following brief statement of 30 the conditions.

In the canning art it is important that the continuous and voluminous stream of cans passing through the line of apparatus shall at no point be interrupted. Serious results 35 and loss of time follow any disarrangement of the can procession, and much care and personal supervision are given to prevent interruption of the stream. This is particularly the case in the matter of feeding the 40 cans into the stream at whatever point in the line, or in connection with whatever machine of the series, it may be necessary to supply or transfer the cans. For the sake of example, I will describe my invention in 45 connection with feeding the cans to a cooker, though it must be understood that my device is applicable to any apparatus or machine to which it is necessary to feed cans with 50 precision and under proper control in order

to inaugurate or to maintain the can-stream 55 continuity.

The object of my invention is to provide a can-feed device which will automatically supply the cans in succession under such conditions of accuracy as to time and position as to insure the continuance and uninterrupted of the can-stream; and to this end my invention consists in the novel can-feed device which I shall now fully describe by reference to the accompanying drawings, 60 65 in which—

Figure 1 is a view, broken, of what may be called a cooker, showing in side elevation the application thereto of my safety can-feed chute.

Fig. 2 is a side view, enlarged, and partly broken, of the can feed chute.

Fig. 3 is a top plan view of the same.

Fig. 4 is a section on the line 4—4 of Fig. 2.

1 is a receptacle, to which the cans are to be fed. For descriptive purposes it may be called a cooker.

2 is the feed chute, the delivery section of which is curved and centrally ribbed at 2', 80 to better guide and swerve the cans to the receptacle inlet 3, thus enabling the chute to be placed parallel with the side of the cooker to save width space. The floor of the chute inclines downwardly to said inlet in order 85 that the cans will roll thereto by gravity.

To the receiving end of the chute is fitted the elevator 4, which carries the cans to the chute.

The chute 2 at one portion or section of its length, (at which section its safety function is performed) has an opening 5 in its floor (Fig. 3), which in the clear is wider than the diameter of the can and but slightly less than the length of the can. On each 95 side of this opening the floor of the chute consists of the can supports or rails 6, forming the horizontal members of the angle-sides 7 of the chute, Fig. 4.

In order to vary and adjust the width of 100 the space or opening 5 between the chute-rails 6, there is fitted within the angle-sides 7 an angle piece 8, which is movable to or from the side, by suitable means, such, for example, as the adjusting screws 9.

The floor of the chute in the approach section to the safety section, rises with relatively wide sides 10, Figs. 2 and 3, which

are elevated above the side rails 6 of the safety opening 5 and terminate in a pronounced drop to said side-rails, as seen in Fig. 2.

- 5 The operation of the chute is as follows. The cans, indicated by 12, are lifted by the elevator 4 and carried positively into the receiving end of the chute and upwardly upon the rising floor sides 10 of the approach 10 section until they surmount the general rise and drop off said sides 10 upon the adjustable angle members 8 of the safety section of the chute. If a can approaches square with the chute and drops true upon members of the safety section, it will bridge the opening 5, and will roll safely thereover and enter the inlet 3 of the box 1. But if the can should approach end on, or upright, or twisted, so that it does not lie square 15 to the chute, it will not bridge the opening 5, but will drop through it, as indicated in Fig. 1, and will be thus automatically removed from the can-stream, and cease to be an obstruction or a menace to the continuity 20 of the stream. Thus the initial insurance of each can's position in the stream, by the automatic discharge of a vitally displaced can, avoids the necessity of personal supervision and attention at this point. This 25 automatic safety feature is due to the intentional relation between the separation of the chute sides and the diameter and length of the can. To render this relation easily variable, so that its function may be accurate, and adapted for different cans, the 30 adjustable supplementary angle members 8 are introduced.

The drop from the raised floor-sides 10 of the approach section down to the safety- 40 section serves to accentuate, as it were, any untrue position of the can, with the result of better insuring its fall through the opening 5. For example, if a can be slightly twisted, that is, one end a little advanced, 45 said end will drop off from the raised floor side 10 first, and the can using the other end as a fulcrum on the other raised floor side 10 will twist still further and thus in-

sure its passage through the opening 5 and out of the can stream. Thus the drop from 50 the floor sides 10 increases the efficiency of the chute.

I claim:

1. A can-feed chute having in one section of its length an opening in its floor of a 55 width greater than the diameter and but little less than the length of the cans to be fed and said chute having an approach section to said open-floor section adapted to direct a can rolling true therein to bridge 60 said floor opening, the floor of said approach section rising to a plane above that of the open-floor section and terminating in a drop to said open-floor section.

2. A can-feed chute having in one section 65 of its length an opening in its floor of a width greater than the diameter and but little less than the length of the cans to be fed and said chute having an approach section to said open-floor section in line there- 70 with adapted to direct a can rolling true therein to bridge said floor opening, and having a delivery section curving at right angles from said floor section, said curved delivery section being longitudinally cen- 75 trally ribbed.

3. A can-feed chute having in one section of its length an opening in its floor of a width greater than the diameter and but little less than the length of the cans to be 80 fed, the walls of the chute on each side of said opening being of angle section; and a supplementary angle member adjustably fitted to the inside of the chute walls, adapt- 85 ed to vary the width of said opening, said chute having an approach section to the open-floor section adapted to direct the can rolling true therein to bridge said floor opening, and the floor of said approach section rising to a plane above that of the 90 open-floor section and terminating in a drop to said last named section.

In testimony whereof I have signed my name to this specification.

ALBERT R. THOMPSON.
